UNITED STATES PATENT OFFICE

90,448

DESIGN FOR A BEVERAGE FAUCET

Charles J. Muend, Philadelphia, Pa.

Application May 13, 1933. Serial No. 48,105

Term of patent 7 years

To all whom it may concern:

Be it known that I, CHARLES J. MUEND, a citizen of the United States, residing in Philadelphia, in the county of Philadelphia, State of Pennsylvania, have invented a new, original, and ornamental Design for a Beverage Faucet, of which the following is a specification, reference being had to the accompanying drawing, forming part thereof.

I claim:—

The ornamental design for a beverage faucet substantially as shown.

CHARLES J. MUEND.
